UNITED STATES PATENT OFFICE.

ALOIS JOSEPH STEPHENS, OF PLAINFIELD, NEW JERSEY.

DESIGN FOR A SHADE-BRACKET.

50,822.

Specification for Design.

Patented May 22, 1917.

Application filed February 14, 1917. Serial No. 148,639. Term of patent 7 years.

To all whom it may concern:

Be it known that I, ALOIS J. STEPHENS, a citizen of the United States, residing at Plainfield, in the county of Union and State of New Jersey, have invented a new, original, and ornamental Design for a Shade-Bracket, of which the following is a specification, reference being had to the accompanying drawing, forming part thereof.

The figure is a side elevation of a shade bracket showing my new design.

I claim:

The ornamental design for a shade bracket, as shown.

ALOIS JOSEPH STEPHENS.

Witnesses:

JAMES LAMBERTSEM,
ALFRED E. NOEL.
